AIR VALVE

Lester Lasher, Salem, Mass.

Application January 10, 1934, Serial No. 706,054

11 Claims. (Cl. 236—63)

My present invention is a novel and improved construction and operation for air release valves, particularly for use on heating radiators or the like.

5 In the usual type of air release valve, as attached to radiators, particularly steam or hot water heating radiators, a valve structure is arranged wherein the valve is open when the radiator is cool, permitting air to enter, and as the 10 heat progresses, the air is driven out through the valve until the steam or hot water reaches the valve, whereupon a float is lifted, a member expanded, or other means actuated to close the 15 valve and prevent further escape of the heating element.

My present invention aims to improve and perfect such valve construction and, furthermore, to provide a novel valve construction whereby individual adjustment for each valve and, hence for 20 each radiator, in each room or compartment may be individually adjusted to effect a closing of the valve at predetermined times or temperatures, thus affording a controlled air venting operation, and similarly controlling the room temperatures 25 afforded by the heating of the radiator to which my improved valve is attached.

It is a further object of the present invention to provide a valve structure suitable for instant and automatic adjustment by the user, so that the action of the valve in closing may be 30 changed from time to time as the individual wishes or requirements of the user vary.

Heretofore such air venting valves have not been constructed to permit such individual adjustment by the user and by unskilled persons and, hence, when the valve was once set, it continued to operate at the same relative time and condition providing its efficiency was not impaired.

40 The usual individual adjustment on radiators was simply to turn the intake off and on, or partly so turned, but so far as applicant is aware, it is a distinct novelty in this art to provide a heating system with air venting valves wherein the air valves individually may be adjusted by the user from time to time.

45 A further important object and advantage of my present invention with individual adjustable air venting valves consists in the fact that I may improve the efficiency of an entire heating system by adjusting the venting valves with relation to their distance from the source of heating supply, thus, in the case of a steam heating system, for example, the radiators and consequently the air vent valves thereon nearest the

heater should be most properly adjusted to function at a predetermined time, while those more remote should be adjusted differently for the greatest efficiency of the entire system.

5 It is to carry out such an improvement in the entire system that my invention is primarily directed. Thus I provide a means for a balanced operation throughout the entire system by adjustment of my automatic air venting and vacuum valves at predetermined points throughout 10 the system.

This individual and improved feature is also a distinct novelty in this art, so far as I am at present informed, and I wish to claim herein this 15 improvement in a heating system broadly of controlled venting, and also controlled intake of air.

Furthermore, it is a distinct novelty of my invention to be able to close the venting valve when there is no heat or water in the radiator or heating system and, thus, no air can pass through 20 the valve either way as an inlet or outlet.

Referring to the drawing illustrating preferred embodiments of my present invention,

Fig. 1 is a vertical view of my valve;

Fig. 2 is a longitudinal cross-sectional view; 25

Fig. 3 is a cross-sectional view showing a modification of the adjusting feature, and

Fig. 4 is a modified form of the check valve structure.

Fig. 5 is a modified form of base with the 30 extension in vertical alignment.

Referring to the drawing, 1 is a base casting or portion of the valve to which the upper cover or casing 2 is threaded, as indicated at 4, and a steam-tight joint is provided by the packing 35 gland 5 and nut 6 threaded on the exterior of the casing 2 and overlapping a washer and adjacent part of the threaded top of the casing 1. Through the recess in the bottom of the casing 1 is secured a hollow sleeve 10 in which an externally threaded cap 12 is fitted, adapted to compress a packing member 13 and washer 14 on the interior, as clearly shown in Fig. 2, giving a steam-tight packing around the stem 15, which is threaded through the sleeve 10 and has a notch 40 16 to permit rotation of the stem to secure a vertical adjustment relative to the sleeve 10 and hence with the base 1. This member 10 is preferably fitted within the base 1 to the end 18 of an adjustable thermostat bellows 20, having 45 the opposite end in the form of a crown or rounded closure 21, which also is preferably formed with a depending stem 22 which will contact with the lower end 18 and limit the collapsing movement of the bellows 20. 50 55

Within the casing 2 is a thermostatic float 25 filled with suitable gas or liquid which will give a quick expansion during the application of heat, which, in combination with the thermostatic action of the bellows 20 gives a double and quick-acting operation for the closing of the valve. The fluid within the bellows 20 is arranged to effect initial expansion of the bellows at a lower temperature than that necessary to cause the float 25 to operate. Thus rising temperatures reaching the valve will cause a gradual expansion of bellows 20 prior to any action by the float 25, since the temperature necessary to cause the float 25 to operate, that is to say, the temperature at which the bottom of the float will snap downwardly, is above that necessary to cause expansion of bellows 20.

It can be seen, therefore, that while the valve has a maximum temperature at which it will close under the positive action of float 25, it may be set to close at lower temperatures under the operation of the bellows 20 alone, the closing temperature being determined by the setting of the valve stem 30 under the influence of the rotatable stem 15. Thus, if the venting opening is restricted by an upward adjustment of valve stem 30 or a downward movement of the seat 31 as in Fig. 3, the valve will close at a relatively low temperature under the influence of the expanding bellows 20. As the initial venting opening is increased the temperature at which closing takes place will increase. The upper limit of closing temperature is determined, however, by the temperature at which the float 25 operates. If the vent has not been closed by the expanding bellows 20 by the time the temperature reaches the operative temperature of the float, the float will then expand and complete the closing of the vent. It should also be pointed out, although it is believed obvious, that expansion of bellows 20 takes place whenever the pressure within the bellows exceeds the pressure without. Thus, if the pressure within the valve casing 2 is reduced below atmospheric, due to collapse of the steam 45 in cooling, bellows 20 will elongate, and if the negative pressure becomes great enough the valve stem 30 may be caused to engage valve seat 31 sealing the valve against incoming air. Preferably the float 25 has the bottom portion 26 of 50 concavo-convex contour, as shown in Figs. 2 and 3, thus giving a centering effect on the crowned portion of the end member 21 and also facilitating the expansion and contraction and hence the quick acting function of the apparatus, as will be 55 readily appreciated. At the upper part of the float 25 is the valve stem 30 adapted to engage a valve seat 31 in the member 32 fitted at the uppermost part of the casing 1, herein shown as threaded in the hub portion of the casing, as 60 indicated at 33, or in any other suitable manner, the upper part of the member 32 providing a check valve seat 34 and in which a ball will rest and prevent air intake. A cap 36 with venting ports 37 and 38 is threaded onto the member 65 32 and permits ready assembly.

Formed preferably as a part of the base 1 is an extension 40, here shown in Figs. 1, 2 and 3 as extending laterally to enable the valve to be attached at one side, although the extension 40 70 may of course be in vertical alignment when desired, as shown in Fig. 5. Preferably, I fit a syphon 41 extending through the extension 40 and of less diameter to allow the steam, air, or water to flow through the extension 40, as shown 75 at 42, around the syphon 41, through the port 44,

and into the chamber 45 and directly in contact with the exterior of the thermostatic bellows 20 and of the float 25, thus affording quick action. No syphon is necessary when the extension 40 is in a vertical position, as in Fig. 5, the condensate readily draining therefrom.

Upon cooling and condensing, the water accumulating in the interior of the base 1 will flow outwardly through the syphon 41.

The operation of the apparatus will now be described. Upon assembly of the parts as shown, an adjustment by rotation of the stem 15 will raise or lower the valve stem 30 so that it will close the valve seat 31 at any desired temperature. Thereupon, when steam is admitted to the radiator to which my valve is attached, the air will escape through the recess 42 and port 44 and out of the valve member 32, lifting the check valve 35 and escaping through the vent ports 37 and 38 until heated vapor enters the valve following the escaping air. Thereupon the thermostat bellows 20 and the thermostatic float 25 will expand, lifting the valve stem 30 and closing the escape from the valve. The fine adjustment permitted by rotating the stem 15 enables the temperature for such valve-closing action to be predetermined as desired.

In the form shown in Fig. 3, I have arranged the adjustable feature at the top of the valve, raising and lowering the valve seat itself by manipulation of the hand-wheel 50. In this form the thermostat bellows 20 is secured to the stem 51 which, in turn, is threaded through a nut 52 in the base 1, and while it may be adjusted during assembly, it is then locked in adjusted position by the cap 53. At the upper part of the casing 2 in this form I apply the valve support 55 to the casing 2, the valve member 56 being rigidly attached to the hand-wheel 50 and being raised or lowered relatively with the casing 2 and valve stem 30 by rotating the hand wheel 50 and the action of the threaded exterior of the valve member 56 on the nut 58, which in turn is threaded within the supporting member 55 and may compress the packing 59, thus rendering a steam-tight joint.

A stop 60 limits the outward movement of the valve seat member, and I preferably form a shouldered portion 61 which will limit the downward position of the valve seat member. A closing nut 62 with venting ports 63 and 64 complete the assemblage.

The operation of this valve is identical with that just described only the valve seat 31 is raised and lowered relatively with the stem 30.

In Fig. 4 a still further modification is illustrated in utilizing a washer or block 70 in place of the check valve 35. In this form the valve seat member 71 is threaded onto the hub of the casing 2 and carries the exterior cap 73 with the venting ports 74 and 75 and is provided with a substantially rectangular space or area of slightly greater dimensions than that of the washer member 70, which latter is proportioned so as to enable it to be lifted easily from its seat, thus allowing the air to pass out the venting port 75 upon a slight rocking or lifting of the washer 70, but will normally rest on the top of the valve seat member 71, closing the same. For this purpose I may utilize a block of any suitable material, leather, rubber, or compound.

For this latter form by utilizing the block 70, the danger of the check valve sticking in the valve seat or otherwise impairing the function

of the valve partly during any long period of idleness, as in summer, is eliminated.

It will be appreciated that my readily adjustable valve structure greatly facilitates the control 5 of the venting in each room, both of the temperature desired and for distance from the boiler, thereby giving balanced radiation and controlled venting throughout an entire heating system.

Thus by an adjustment of the capacity of the 10 air vents in any radiator, the heat supply can be induced into or repelled from the radiator so adjusted.

Furthermore, if a plurality of radiators are equipped, each with my improved valve, the entire 15 set may be so adjusted as to function in balanced relation proportional to the distance, pipe, bends, or other conditions so that the radiators will all be in substantially equal heat-receiving relation. Thus, by way of example, let it be presumed that 20 it is desired to have the radiators in the living room of the house so adjusted that the thermostat will automatically close the same when the temperature in the radiator of 150 to 160° F. has been reached. By adjusting the operation 25 of the thermostat bellows 20 toward or from the valve seat—or adjusting the valve seat toward and from the valve stem—this radiator can be caused to close at a temperature of approximately 150 to 160° F. Another radiator in the system, 30 in the bathroom for example, can be adjusted to close thermostatically at a higher temperature, 180 to 190° F. by way of illustration.

I believe that my improved adjustable thermostatic temperature control valve invention, and 35 the adjustment of an entire heating system in balanced relation as above explained is distinctly new in this art, and I wish to claim the same herein broadly.

I claim:

40 1. In a radiator air venting valve, a base, a shell having a vent mounted on said base, dual thermostatic means mounted on the base, one of said means capable of closing said vent instantly, the other means capable of closing said vent 45 gradually, at least one of said means being a hollow sealed member.

2. A radiator air venting valve comprising a shell with a vent therein, adjustable thermostatically operated vent closing means, said 50 means comprising a first thermostatic means capable of gradually closing said vent at selected temperatures and a second thermostatic means capable of closing said vent instantly in conjunction with said first means at a temperature 55 higher than said selected temperatures, at least one of said means being a hollow sealed member.

3. An automatic air venting valve for steam radiators comprising an outer casing, a vent therein and vent closing means within said casing, 60 said means comprising a hollow water-tight thermostatic float mounted on a thermostatic bellows, said bellows arranged to expand prior to the expansion of said float.

4. An automatic air venting valve for steam radiators in which the vent closing means comprises a hollow water-tight thermostatic float 65 and a thermostatic bellows arranged axially of each other, an adjustment for varying the vent-

ing capacity, said bellows through part of the range of adjustment being capable of closing said vent without the actuation of said float.

5. In an automatic air venting valve for steam radiators including a casing with a vent, the 5 combination of two thermostatically operated units, one of which is a hollow sealed member, one of said units arranged to expand gradually under the influence of heat, the other arranged to expand suddenly under the influence of heat, 10 the co-action of said units resulting in closing said vent.

6. In a radiator air venting valve, a base, a casing detachably mounted thereon, a vent including a valve seat in said casing, longitudinally 15 adjustable thermostatically operated means for closing said vent, said means comprising a thermostatic bellows adjustably mounted on said base, a hollow water-tight thermostatic float supported by said bellows, said bellows operating at temper- 20 atures lower than the float operating temperature.

7. In an automatic air venting valve for steam radiators, valve closing means comprising a thermostatic float arranged to actuate said valve closing means instantly at a pre-determined temperature and a thermostatic bellows arranged to gradually close said valve closing means under the influence of increasing temperatures lower than said pre-determined temperature. 25

8. An automatic air venting valve for steam 30 radiators, having dual thermostatic controls, one of said controls operating to close the valve gradually under increasing temperatures below a pre-determined temperature, the other of said controls operating to complete the closing instantly 35 when the temperature reaches the predetermined temperature at least one of said means being a hollow sealed member.

9. In a venting valve for steam radiators, a casing with a vent therein, closing means for 40 said vent comprising a hollow watertight thermostatic float and a substantially noncollapsible bellows, both the float and bellows mounted in said casing on an adjustable stem to which said bellows is attached, elongation of the float and 45 bellows being caused by pressure differences.

10. A venting valve for steam radiators comprising a casing with a vent therein and a base and means for closing said vent comprising a hollow watertight thermostatic float, said float 50 supported by a bellows permanently mounted on an adjustable stem threaded into said base, said bellows capable of axial expansion under the influence of pressure greater than the internal valve pressure but substantially incapable of collapse when said pressure is less than the internal 55 valve pressure.

11. In a radiator air venting valve, a casing having a vent, and means mounted in said casing for closing said vent comprising a hollow water-tight sealed thermostatic float, a bellows supporting said float and adjustably mounted in said casing on an adjustable stem to which it is affixed, said bellows operated by pressure differences but substantially incapable of compression below its 60 normal length. 65

LESTER LASHER.
